T. H. EDELBLUTE

TRACK BRACE

Filed Jan. 17, 1925

Thomas H. Edeblute, INVENTOR
BY Charles Doolittle
ATTORNEYS.

UNITED STATES PATENT OFFICE.

THOMAS H. EDELBLUTE, OF PITTSBURGH, PENNSYLVANIA.

TRACK BRACE.

Application filed January 17, 1925, Serial No. 3,038.

To all whom it may concern:

Be it known that I, THOMAS H. EDELBLUTE, a citizen of the United States, residing at Pittsburgh, in the county of Allegheny and State of Pennsylvania, have invented certain new and useful Improvements in Track Braces, of which the following is a specification.

This invention is an improvement in rail or track braces, and particularly to track braces which are adjustable for rails of different sizes.

Track braces of various forms have been devised and are largely used on railroads at curves and other points to supplement the wooden ties and hold the rails from spreading. They are also used in conjunction with and entirely without wooden ties on temporary trackage, sidings, etc.

The present invention has for its principal objects to provide an adjustable track brace of extremely rigid construction, which can be easily and quickly applied to the rails, or removed therefrom, and which will securely hold the rails from spreading. It is particularly designed for use in temporary trackage in and around mines, where ties are frequently not used, and where rails of different sizes are commonly found. It is, however, equally adaptable for use on railroads.

The nature of the invention may be readily understood by reference to the accompanying drawings, wherein:

Fig. 1 is a side view of the brace applied to a track;

Fig. 2 is an exploded perspective view of the several parts of the rail engaging clamps of the brace;

Fig. 3 is an enlarged view similar to Fig. 1, showing one of the clamps in detail, parts of the clamp being shown in section; and

Fig. 4 is a transverse section in the plane of line IV—IV of Fig. 3.

In the drawings, A designates the tie rod which extends across the track and which is longer than the width of the track. Its ends are threaded, as designated at 2, for a considerable length. The two rails are designated X.

At each end of the tie rod are the adjustable rail engaging clamps. These clamps comprise three principal parts B, C and D.

Part B is the central member. It is generally square or flat sided in cross section

and has an opening extending longitudinally therethrough and into which the threaded part of the tie rod is slidably fitted. On its lower surface is an inclined portion 3 of decreasing thickness toward the inner end. 60 The top 4 is flat, to provide a seat for the rail, and its outer end 5 is preferably inwardly beveled a very slight degree from its top down. Projecting beyond the top of the outer end of the member B is a small 65 lug 6, for the purpose hereinafter described.

Member C goes to the inside of the rail. It is in the form of an elongated body having a generally squared flat-sided opening 7 extending throughout the greater portion 70 of its length, the bottom 7a of this opening being inclined to conform to the inclination of part 3 of member B. The inner end of member B may thus be slidably and non-rotatably telescoped into member C. The 75 extreme inner end of member C has a vertically elongated opening 8 therein through which the tie rod is slidably passed, the vertical elongation permitting of the vertical movement of member C with respect to the tie rod and the member B. Such vertical movement occurs when the member C is moved on the member B, the coacting inclined surfaces serving to raise or lower the member C to thus effect adjustment for rails of different sizes, as will be hereinafter more 80 fully explained. On the member C is an overhanging rail flange engaging lip or projection 9. A reinforcing rib may be provided at 10. 85

Inside of the member C is a washer 11 and nut 12 threaded on the tie rod, which serve to adjustably confine the movement of the clamp.

The member D has a vertical part 13 and an overhanging lip or rail engaging portion 16. Passing through the vertical part 13 is a vertically extending slot through which the outer end of the tie rod passes. Part 13 has its inner face 15 inclined outwardly toward its upper end, so that it is slightly wedge shaped. The inclined face 15 bears against and cooperates with the inclined face 5 of member B. 95

In the member D is a flat-sided recess 17 into which lug 6 of member B extends. Upon examination of Fig. 3, it will be seen that, when the parts are in rail clamping position, the lug 6 is entirely out of contact with the rail X, the recess 17 being deep 100 105

110

enough to allow this. This is so that the clamping action of member D will not be interfered with.

The lug and recess are provided to facilitate the application of the clamp to the rail. In the first place, these interfitting parts hold the member D from turning, while the clamp is being fixed. The lug 6 also prevents member B from slipping back under the rail during the initial adjustment of the clamp.

On the outer end of the shaft is a second washer 18 and a nut 19.

In operation, the parts are first loosely applied to the rail, and the nuts 12 and 19 are then taken up. As members B and C telescope, the coacting inclined surfaces 3 and 7^a force part 9 and surface 4 into tight rail-flange clamping position. Due to the fact that, while rails of different sizes have flanges of different thickness, but of the same general angular inclination, the clamp will automatically adjust itself to rails of varying sizes within a given range.

The member D is forced into rail-flange clamping position by nut 19. When it is at the proper height to clamp the rail, nut 19 is taken up tight, and the wedge shape of the part 13 prevents member D from being forced up after the nut is tight.

It will be understood that the object of slots 14 and 8 are for the purpose of permitting such vertical adjustment of the two clamping members with respect to the rod as may be necessary for the varying sizes of rails. It is further proposed that the clamp may be made in various sizes, each size to take care of a certain range of rail sizes.

The clamp as thus constructed firmly holds the rail between the two end members and the single central member. It is adjustable as to width and height, and each clamping unit is adjustable on the tie rod to different gauges. Due to the few parts employed, and the interfitting relation of such parts, the brace can be easily handled and applied to the rail. The construction of the parts is such that they can be cheaply cast without subsequent machining.

I claim:

1. A rail brace including a tie rod and an adjustable rail engaging clamp on the tie rod, said clamp including a central clamping member adapted to engage the under side of a rail and through which the tie rod is slidably passed, said central member being beveled at one end and having an inclined bottom face tapering toward its other end, a vertically slotted flange-engaging clip engaging the inclined end of the central member, a vertically slotted flange clip telescopingly engaging the other end of the body, and nuts on the tie rod for confining the parts against movement.

2. In a rail brace, a tie rod, and a clamp on the tie rod having a central member adapted to engage the under side of the rail, a vertically adjustable clip at each end of the adjustable member for engaging the edges and top surface of a rail, one of said clip members abutting against the central member, the other telescopingly engaging the central member, and an angular face on the central member for cooperation with the clip telescopingly engaged therewith.

3. In a rail brace, a tie rod, and a clamp carried by the tie rod comprising three co-operating members, said members including a central member on which a rail may seat, a vertically adjustable hook-like clamping member at one end of the central member, a second hook-like clamping member having a body portion into which a part of the other end of the central member telescopes, said central member and second hook-like clamping member having cooperating inclined surfaces to effect a vertical adjustment of said second clamping member when it is moved longitudinally of the central member, and nuts on the tie rod for holding the parts in adjusted position.

4. A track brace including a tie rod having a threaded end portion, a rail engaging element fitted onto the threaded end of the tie rod, said member having its outer end inclined inwardly from the top down, and having an inclined bottom surface near its other end, a rail clamping member at the inclined end of the body having an inclined face for cooperation with such inclined face of the body, a second rail clamping member telescopingly fitted over the other end of the first member, said rail clamping members having vertical slots therein through which the tie rod passes, and nuts on the tie rod for confining the parts against movement.

5. A track brace including a tie rod having a threaded end portion, a rail engaging element fitted onto the threaded end of the tie rod, said member having a substantially flat top surface, and having substantially flat sides, the bottom face thereof near one end being inclined, a rail flange confining and clamping member telescopingly fitted over the inclined end of said first element, said rail flange clamping member having a cavity therein to receive and cooperate with the flat sides and inclined bottom of the first element, a second rail flange clamping member at the other end of said first element and vertically adjustable with respect thereto, said tie rod passing through both of said rail clamping members, and nuts on the tie rod for holding the clamping members in rail clamping position.

6. A track brace including a tie rod, a central rail engaging element fitted on the tie rod, said central element having an in-

wardly beveled face from the top down at one end, and having an inclined bottom surface at its other end, a rail clamping member telescopingly and non-rotatably fitted 5 over the end having the inclined bottom, the end of said element which is beveled having a lug projecting longitudinally therefrom, and a second rail clamping member at the beveled end of said element and having an 10 inclined face for cooperation with the beveled end of said element, the second rail clamping member having a groove therein

into which the lug on said element extends, the interfitting lug and groove serving to hold the said second clamping member 15 against rotation, said groove being of sufficient depth to entirely receive the lug, whereby the lug may be kept out of contact with a rail being clamped, each of said rail clamping members having a vertical slot 20 therein through which the tie rod passes, and nuts on the tie rod.

In testimony whereof I affix my signature.
THOMAS H. EDELBLUTE.
